UNITED STATES PATENT OFFICE.

FRANK J. GILROY, OF BUFFALO, NEW YORK.

HEATING FLUIDS MECHANICALLY.

No. 823,856.

Specification of Letters Patent.

Patented June 19, 1906.

Application filed March 18, 1903. Serial No. 148,369.

To all whom it may concern:

Be it known that I, FRANK J. GILROY, a citizen of the United States, residing at Buffalo, in the county of Erie and State of New York, have invented certain new and useful Improvements in Heating Fluids Mechanically, of which the following is a specification.

My invention relates to heating fluids by forcing them through certain channels in solid bodies consisting of one or more pieces. The devices have proved effective, practically, in heating air; but other fluids may obviously be heated in like manner. The invention has been embodied in various ways, some of which are illustrated in the accompanying drawings, in which—

Figure 1 is a sectional view showing part of an air-compressor having my devices connected therewith. Fig. 2 is an axial section through the air-heating body, which in this instance is a peculiar valve. Figs. 3 and 4 show, respectively, the meeting faces of two coacting parts of said valve. Figs. 5 and 6 are views similar to Figs. 3 and 4, showing a different construction of the valve. Fig. 7 is a fragmentary perspective view showing a different arrangement of the air-passages through the heating-body. Figs. 8 and 9 are respectively side view and section of a portion of a body having its passages arranged differently from those in any of the other forms. Fig. 10 is a section similar to Fig. 9, showing a slight modification of the form shown in the latter figure. Fig. 11 is a perspective view showing a broad passage between corrugated plates forming the main part of the heating-body.

In Figs. 1, 2, 3, and 4, A represents an air-compressor cylinder; B, a plunger therein; C, an inlet-valve, and D the body of a valve fixed in the wall of the cylinder to govern the escape of compressed air therefrom. A pipe E incloses the valve and conveys the escaping air to any desired point. This valve D is shown as consisting of a seat member F, fixed in the wall of the cylinder and having an axial rod G supported by arms H, extending inward from the walls of a large central opening I in the member F. Upon its outer side this member is recessed to receive a second member J, sliding upon the rod G and normally held in its seat in the member F by a spring K, whose tension may be regulated by nuts L upon the free threaded end of the rod G. The working side of the member J is accurately turned to cone-pulley form, so

that this side of the member consists of a series of short cylindrical portions whose annular end faces are in planes perpendicular to the valve's axis. Preferably each cylindrical portion is provided with a series of marginal notches M, formed by removing a wedge-like portion, so that when the two parts of the valve are together these notches form tapering passages. The notches in successive portions are not in the same radial planes, so that any air passing in one notch must pass around the cylinder to enter another notch. The working side of the seat member is so formed that the end faces of the member J rest against corresponding parts of the seat when the valve is closed; but the diameters of the cylindrical parts of the seat are slightly greater than those of the corresponding parts of the part J. If the spring be adjusted to press the member J toward its seat with moderate force, the advance of the plunger will overcome the force of the spring by urging compressed air against the inner face of the member J, thereby moving the latter slightly from its seat and allowing air to pass and escape into the pipe E from all sides of the valve. The air thus escaping will be found to be highly heated, it being quite feasible to render the pipe E incandescent while holding the hand upon the wall of the non-jacketed compressor-cylinder.

In Figs. 5 and 6 I have shown a valve made up of a series of superposed plates N N' N² N³, held together by bolts O, each provided with numerous perforations and each having on its outer face a marginal rim P, holding its central portion at a slight distance from its neighbor, or, in the case of the outer plate, forming a seat for the moving valve member or cap Q, which, as before, is pressed to its seat by a spring Q'. The perforations in each plate are preferably out of registry with those in the succeeding plate. The annular chambers between the plates are preferably made of progressively-increasing diameters in analogy with the plane-walled spaces in the valve of the form first described.

Fig. 7 shows a portion of a heating-body in which the passages R are concentric and oppositely inclined, so that thin sheets of air in passing through each plate impinge upon each other even more sharply than in the forms before mentioned, and this is repeated as many times as may be desired by merely increasing the number of plates. As shown, each plate is made up of beveled rings S, held

in proper relation by bars S'. The valve or heating-body, which is not necessarily a valve, may be made up of perforated plates T, Figs. 8, 9, having registering perforations 5 T', but those in alternate plates being larger than those in intermediate plates. Fig. 10 is a view similar to Fig. 9, showing uniformly perforated plates each having its perforations countersunk.

10 Fig. 11 shows the heating-body as consisting of two corrugated plates U and side plates U', preventing the lateral escape of the air.

What I claim is—

15 1. For heating fluids, the combination with a body traversed by an attenuated passage whose walls are capable of relative lateral movement, of means for forcing fluid through said passage, and means for opposing yielding resistance to increasing the distance between its opposite walls.

20 2. For heating fluids, the combination with a body having an attenuated passage therethrough, of means for forcing fluid through said passage, and means for opposing yielding resistance to the escape of fluid from the mouth of said passage.

25 3. For heating fluids, the combination with a body having an attenuated passage, there-through, whose cross-sectional area varies repeatedly, of means for forcing fluid through said passage.

30 4. For heating fluids, the combination with a body traversed by a narrow passage having

forwardly-convergent portions, of means for 35 forcing fluid through said passage.

5. For heating fluids, the combination with a body traversed by a capillary passage having broad parallel walls, of means for forcing fluid through said passage. 40

6. For heating fluids, the combination with a body traversed by a capillary passage having broad, walls changing in direction at successive points, and means for forcing fluid through said passage. 45

7. For heating fluids, the combination with a chamber having an exit adapted to permit a large stream of fluid to pass, of means for subjecting fluid in said chamber to pressure, and means for compelling all portions of the 50 escaping stream to assume an attenuated form and pass between only slightly-separated passage-walls, whereby the contact-surface of the stream with the walls is made very great. 55

8. For heating fluids, the combination with a body channeled to form capillary paths which merge, of means for forcing fluid under pressure to pass along said paths through said body. 60

In testimony whereof I have signed my name to this specification in presence of two witnesses.

FRANK J. GILROY.
